DESIGN FOR A COMBINED STROLLER AND PACKAGE CARRIER

Jesse E. Du Bois, Jackson Heights, N. Y.

Application August 6, 1943, Serial No. 110,847

Term of patent 14 years

(Cl. D14—14)

To all whom it may concern:

Be it known that I, Jesse E. Du Bois, a citizen of the United States, residing at Jackson Heights, county of Queens, and State of New York, have invented a new, original, and ornamental Design for a Combined Stroller and Package Carrier, of which the following is a specification, reference being had to the accompanying drawing, forming part thereof.

In the drawing,

Fig. 1 is a front perspective view of a combined stroller and package carrier showing my new design; and

Fig. 2 is a rear perspective view thereof.

I claim:

The ornamental design for a combined stroller and package carrier, substantially as shown.

JESSE E. DU BOIS.
